RUDDER ASSEMBLY

Theodore Sprague, IV, New Orleans, La., assignor
to Andrew J. Higgins, New Orleans, La.

Application November 23, 1945, Serial No. 630,159

7 Claims. (Cl. 114—169)

1

This invention relates to rudder assemblies for boats.

An object of the invention is the provision of a rudder assembly in which a support for the rudder and rudder stock is secured to the bottom of a boat, such as a runabout, a sleeve depending from the bottom of the support having therein a leak-proof grease chamber of sufficient capacity to supply lubricant to the rotatable stock and associated bearings for an entire season.

Another object of the invention is the provision of a rudder assembly in which a removable means is connected to a fixed part of the assembly with a ring at the upper end of said means above the deck, the fixed part of the assembly being secured to the bottom planking of a boat so that the strain of lifting is eliminated from the deck.

A further object of the invention is the provision of a rudder assembly in which the rudder and stock are formed in one piece with the stock being mounted in spaced bearings formed on a reinforced bracket which is provided with a base plate secured to the bottom planking of a boat, a sleeve depending from said base plate and enclosing a portion of the stock and having a chamber therein for lubricant which is in contact with the enclosed portion of said stock, said chamber being sealed against the loss of lubricant.

A still further object of the invention is the provision of a rudder assembly in which a stock forming a rotatable shaft for a rudder is mounted in spaced bearings of a support mounted on the bottom planking of a boat, said stock having a cylindrical portion, and a lower tapered portion, a sleeve depending from the support forming one of the bearings and having a lubricant chamber therein surrounding the lower tapered portion, a ring of greater diameter than the base of the tapered portion fitting neatly into an annular groove in the lower end of the sleeve and formed integrally with the stock.

The invention may be further briefly summarized as consisting in certain novel details of construction and combinations and arrangements of parts which are illustrated in the accompanying drawings, which will be described in the specification, and set forth in the appended claims.

The structure which embodies the features of the invention is illustrated clearly in the accompanying drawings, in which:

Figure 1 is a longitudinal side view of a boat showing my invention applied thereto;

Figure 2 is an enlarged vertical section of the rudder assembly, and

2

Figure 3 is a view in perspective of the rudder assembly, with the parts in detached relation.

Referring more particularly to the drawings, 10 designates a pleasure boat having a keel 11, a bottom planking 12, and deck portions 13 and 14.

The forward end of the boat is provided with a Sampson post 15 having a plate 16 on the lower end which is secured in any suitable manner to the bottom planking 12. This post rises through the deck 13 and has an eye 17 to receive a ring 18, to which is adapted to be attached an elevating rope or cable (not shown).

The rear end or stern of the boat is equipped 15 with a rudder assembly, generally designated by the numeral 20. The assembly includes a casting in the form of a bracket 21, which has an internally threaded socket 22 to receive the lower threaded portion of a lifting rod 23. This rod 20 extends upwardly through an opening in the deck portion 14 where it terminates in an eye 24, receiving a ring 25. A base plate 26 of the bracket is bolted to the inner face of the bottom planking 12. A rope or cable may be attached removably 25 to the ring 25. It will be noted from this construction that when the boat is raised or lowered by any form of lifting means, no strain is placed on the deck, either at the bow or stern of the boat, since the Sampson post 15 and the bracket 30 20 are secured to a more stable part, such as the bottom planking 12.

The rudder assembly includes the bracket 21, having the flat base plate 26, an upstanding rear wall 27 and a forwardly projecting web 28 which 35 not only reinforces the bracket by its integral connection between rear wall 27 and the base plate 26, but which provides a bearing 29 for the upper end of a stock 30.

The upper end of the stock is cylindrical, as 40 shown at 31, to receive a lock collar 32. The collar and upper end of the stock have aligned perforations to receive a cotter pin (not shown), by which the collar is secured. An intermediate portion 33 of the stock is tapered and this tapered portion merges into an intermediate cylindrical portion 34 and terminates in a frusto-conical portion 35 and a cylindrical flange 36 of greater diameter than the base of the portion 35.

A rudder 37 which forms a one piece construction with the stock 30, depends from the stock below the bottom of the boat. The inner edge of the rudder is tapered and streamlined.

A sleeve 40 depends from the under face of the base plate 26 and in axial alignment with an opening 41 in said plate through which the stock 30

projects. This sleeve as shown more particularly in Figure 2, has a chamber 42 for lubricants, surrounding the frusto-conical portion 35 of the stock 30. The sleeve has a shoulder 43, which rests upon the top of the flange 36 on said stock. The lower end of the sleeve terminates in a flange 43' which houses the flange 36, and the sleeve 40 has a tapered zone 52 above the shoulder 43, which is in rotary sliding contact with the lower part of the frusto-conical portion 35 of the stock. In other words, the stock and sleeve have interfitting and complementary portions to prevent the loss of lubricant. A bushing 44 is seated in a bore 45, in the upper portion of the sleeve, and prevents the loss of lubricant from the chamber 42. The sleeve passes through an opening in the bottom of the boat.

An operating arm 46 for the rudder 37 has an eye 47 at one end, which is received upon the cylindrical portion 34 of the stock adjacent the lower end of the tapered portion 33 of said stock. The inner wall of the eye 47 is provided with a key 48, which fits into a slot 49 formed in the stock, so that the arm 46 may be readily removed, when desired, and will rotate said stock when the arm is manipulated.

A channel 50 is formed in the sleeve 40, and connects the interior of the chamber 42 with a grease nipple 51. Said channel extends through the base plate 26, the nipple being threaded into the mouth of the channel.

In order to remove the rudder from the assembly, it is only necessary to pull the cotterpin, remove the collar 32 from the upper end of the stock 30, whence the rudder and stock may be unshipped by tapping on the upper end of the stock until the arm 46 contacts the plate 26. Further tapping upon the end of the stock pushes the arm 46 off of the stock.

While I have in the above description disclosed what I believe to be a preferred and practical embodiment of the invention, it will be understood to those skilled in the art that the specific details of construction as shown and described are by way of example and not to be construed as limiting the scope of the invention.

What I claim as my invention is:

1. A rudder assembly comprising a bracket having bearings thereon, a rudder stock mounted in the bearings, one of the bearings being in the form of a sleeve depending from said bracket, said stock having a frusto-conical portion in the sleeve, said sleeve adjacent the frusto-conical portion being hollowed out to form an annular chamber for lubricant, and a flange on the stock at the base of the conical portion, the sleeve having a shouldered recess neatly fitting said flange.

2. A rudder assembly comprising a bracket having a base portion, bearings on the bracket, a rudder stock received by the bearings, one of the bearings including a sleeve depending from the base portion, said stock having an enlarged portion within the sleeve, said sleeve having a hollowed-out portion surrounding the enlarged portion to form a chamber for lubricant, the base portion having a nipple thereon, the base portion and sleeve being provided with a channel con-

necting the chamber with the nipple for supplying lubricant to said chamber, and complementary shouldered portions on the sleeve and stock for preventing the loss of lubricant from the sleeve.

3. In a rudder assembly for a boat, a bracket secured to the bottom of said boat for supporting a rudder and a related rotatable shaft for said rudder, said bracket having an internally threaded socket, a rod having an eye at one end, the other end of said rod being threaded into the socket so that when a cable is secured to said eye, the boat may be raised with the strain being placed on the bottom of the boat.

4. In a rudder assembly for a boat, a bracket secured to the bottom planking of said boat for supporting a rotatable shaft and a rudder connected to the lower end of the shaft, a rod extending upwardly from the bracket and through the deck of said boat, means connecting the rod to the bracket, and means on the upper end of the rod for attaching the rod to a lifting cable so that when the boat is raised the strain will be placed on the bottom planking.

5. A rudder assembly for a boat comprising a bracket having a base secured to the bottom of a boat, bearings on the bracket, a rudder stock received by the bearings, one bearing depending from the base and passing through the bottom of the boat, the last mentioned bearing having a chamber therein for lubricant, the stock where embraced by the chamber in said bearing having a tapered enlargement providing an annular inclined wall to the chamber, the base and last mentioned bearing having a common channel for supplying lubricant to the chamber.

6. Rudder assembly comprising a bracket having an integral base plate adapted to be bolted to the keel, and, angularly thereto, an integral transom plate adapted to be bolted to the transom, an integral web rising from the rear of said base plate along the intermediate part of said transom plate having a forwardly directed upper arm, said base plate having on the side opposite said web and forwardly thereof, a projecting cylindrical flange, aligned bearings in said arm and base plate coaxial with said flange, a rudder having a shaft journaled in said bearings, having a portion closing the lower end of said cylindrical flange forming therewith a sealed grease reservoir about said rudder shaft, and an operating member keyed to said rudder shaft between said bearings.

7. Rudder assembly as claimed in claim 6, said bracket having an upwardly directed socket adapted to detachably receive a rod for securing a mooring bitt.
